UNITED STATES PATENT OFFICE.

JOHN KIEWICZ, OF HYDE PARK, MASSACHUSETTS, ASSIGNOR TO THE REECE BUTTON HOLE MACHINE COMPANY, OF BOSTON, MASSACHUSETTS, A CORPORATION OF MAINE.

THREAD-HOLDING DEVICE.

1,111,907.

Specification of Letters Patent. Patented Sept. 29, 1914.

Original application filed April 18, 1912, Serial No. 691,652. Divided and this application filed May 13, 1913. Serial No. 767,298.

To all whom it may concern:

Be it known that I, JOHN KIEWICZ, a citizen of the United States, residing at Hyde Park, in the county of Suffolk and State of Massachusetts, have invented certain new and useful Improvements in Thread-Holding Devices, of which the following is a specification, reference being had therein to the accompanying drawing.

10 This invention relates to thread holding devices such, for example, as are adapted to be attached to sewing machines for securing the loose thread end at the beginning of a sewing operation.

15 For convenience, the present invention is shown as applied to a portion of a machine for attaching buttons to fabric. The novel thread holding device is shown associated with the work plate of such a button attaching machine as is illustrated in my prior co-pending application Serial No. 691,652, filed April 18, 1912, of which prior application this present application is a division.

20 The main object of the present improvement is to increase the simplicity and also the durability of thread holding devices while retaining equal or greater efficiency than prior known devices.

25 Other objects will be stated in the hereinafter following description or will be apparent to those skilled in the art.

30 To the attainment of such objects the present invention consists in the novel constructions, features and combinations described and illustrated herein.

35 First will be described one form of thread holding device embodying the present improvements, and thereafter the novel features will be pointed out in the claims.

40 In the accompanying drawings forming a part hereof, Figure 1 is a left-hand elevation of a sewing machine work support together with thread holding device carried thereby; Fig. 2 is a top view of the parts shown in Fig. 1; Fig. 3 is an enlarged partial vertical section of the work support and thread holder shown in the other figures.

45 Similar letters of reference designate corresponding parts in the several figures of the drawings.

50 While in the annexed drawings the novel thread holding device hereof is shown associated with the work support, it might in some cases be associated with the opposed

work clamping member or presser foot. 55 Sewing mechanism although not illustrated will be understood.

The invention comprises in combination with one of the work clamping members, preferably the work support, a thread holding device which consists of an elongated spring member whose holding end presses against the work clamping member and whose other end is secured so as to allow play of the holding end, the parts being so 60 constructed and relatively arranged as to restrict the play of the spring member between narrow defined limits of movement.

The details of the sewing mechanism and work support need not be referred to excepting to state that the work support F comprises a substantially horizontal plate f centrally slotted at f' to permit the sewing operations. The improved thread holder mounted thereon is shown as consisting of 75 an elongated spring member M, whose one end is secured at m, so as to permit play or movement of the other end, which latter is the holding end m' coöperating with the plate f for holding a thread between them. 80

There has been a difficulty with the ordinary thread holding device that the forcible engagement of heavy thread therein oft repeated, gradually bends and wears the device so as to sometimes destroy it or at least 85 impair its efficiency. These objections were trie of the type of holding device consisting of a short piece or tongue struck out of the material of a sheet metal part such as the work support. Such objections are entirely 90 overcome in the present improvement, in which is comprised an elongated member controlled by spring action, so arranged as to coöperate with another member for holding the thread between them, the elongated 95 holding device having a degree of play about a distant point, namely its farther end, so that no wear or destruction is probable. The holding device M is shown as consisting of a piece of elastic wire fixed by 100 a screw at m and yielding at its other end by reason of the play of its own elasticity. An effective construction and fitting of the device is that shown, wherein the spring wire M is reversely bent at an intermediate portion so as to pass through an aperture in the plate f, the extreme end m' only showing to view above the work support. The tend-

ency of the spring action is to hold the end m' of the spring member M downwardly in pressing contact with the plate f, while the aperture in said plate is sufficiently large to permit the holding end m' to slightly rise for the admission of the thread, and the extreme end of the wire is beveled as shown to facilitate the thrusting of the thread into the thread holder.

10 The improvement may be expressed as a device for holding thread ends on sewing machines which device comprises the combination of the following elements, namely, a fixed plate-like portion F of a sewing machine, an elongated spring strip member M shaped and arranged to have its thread holding end m' pressing flatwise directly against said fixed member with the thread between them and its other end stationarily 15 secured to the fixed member; and the mentioned parts so constructed as to restrict the play of the strip member within narrow limits, namely, by reason of the strip member having its secured end at one side of the fixed member and its holding end at the opposite side.

It will thus be seen that a thread holding device has been described which embodies the principles and attains the objects and 20 advantages before referred to, and other advantages will be apparent to those skilled in the art.

While the improvement has been described in detail, obviously matters of detail and 25 form may be indefinitely varied within the principles of the improvement and, therefore, no restriction to such matters of detail or form is intended excepting as set forth in the appended claims.

40 What is claimed is:

1. A device for holding thread ends on sewing machines comprising in combination

with a fixed plate-like portion of a sewing machine, an elongated spring strip member, shaped and arranged to have its thread holding end pressing flatwise directly against said fixed member with the thread between them and its other end stationarily secured to said fixed member, said strip member having its secured end at one side 45 of the fixed member, and its holding end at the opposite side.

2. A device for holding thread ends on sewing machines comprising in combination with a fixed plate-like portion of a sewing machine, an elongated spring strip member, shaped and arranged to have its thread holding end pressing flatwise directly against said fixed member with the thread between them and its other end stationarily secured 50 to said fixed member, said strip member having its secured end at one side of the fixed member, and its holding end at the opposite side, and reversely bent at the point of passing the fixed member's plane. 55

3. A device for holding thread ends on sewing machines comprising in combination with a fixed plate-like portion of a sewing machine, an elongated spring strip member, shaped and arranged to have its thread holding end pressing flatwise directly against said fixed member with the thread between them and its other end stationarily secured to said fixed member, the fixed member having an aperture, and the strip member passing through said aperture and there reversely bent so that its two ends lie 70 against opposite faces of the fixed member. 75

In testimony whereof I affix my signature in presence of two witnesses.

JOHN KIEWICZ.
